Inventor:

*Henry K. Sandell,
Baptist, La., Christian Name,*

UNITED STATES PATENT OFFICE.

HENRY K. SANDELL, OF CHICAGO, ILLINOIS, ASSIGNOR TO HERBERT S. MILLS, OF CHICAGO, ILLINOIS.

SOUND RECORD.

Application filed February 26, 1921. Serial No. 447,927.

To all whom it may concern:

Be it known that I, HENRY K. SANDELL, a citizen of the United States, residing at 221 South Green Street, Chicago, in the county of Cook and State of Illinois, have invented a new and useful Improvement in Sound Records, of which the following is a specification.

In accordance with the present invention 10 a sound record, for example, of the disk type, is prepared having an auxiliary groove for the return of the tone arm from the end of the sound record groove or spiral to its beginning. A record provided with such 15 a groove is illustrated in the accompanying drawing, in which—

Fig. 1 is a plan view of a record, and

Fig. 2 a partial sectional view thereof.

The numeral 5 indicates a disk record, of 20 which the annular space 6 is provided with a spiral sound record groove and the circular space 7 surrounding the central opening 8 is provided with the label. Outside the space 6 is an annular space 9 having a plane 25 surface, and between the annular space 6 and the central circular space 7 is an annular space 10 having a plane surface.

In addition to the spiral sound record groove occupying the space 6 a groove 11 30 is formed in the record for returning the freely-movable tone arm from the end of the sound record groove to its beginning. This groove starts in the record groove spiral after the termination of the sound 35 waves, traverses the surface 10, the label surface 7, if necessary, and the spiral groove 6, entering the surface 9 with a re-entrant curve which returns it to the initial portion 40 of the groove portion 6. The pitch of the initial portion 11^a of the groove 11 is slightly greater than that of the grooves of the groove portion 6 and increases, rapidly, preferably as a cycloid curve, and thereby causes the tone arm to travel rapidly out 45 of the area 6. The curvature of the groove 11 is preferably such as to carry the tone arm to the beginning of the record groove in less than one complete revolution of the record, and preferably in more than $\frac{3}{4}$ revolu-

tion. The terminal portion 11^b of the 50 groove 11 is curved to merge into the spiral groove in area 6. The groove 11 is made of slightly greater depth than the sound record groove, its edges being clean cut in order that the passage of the sound reproducing 55 stylus over the across groove 11 will not result in a click or other noise.

In playing the record with an instrument having a freely swinging tone arm, the needle is placed in the spiral groove in the 60 space 6, and is carried by that groove across the said space. When it reaches the initial portion 11^a of groove 11 it is carried by that groove across the record and across the space 6 provided with the record groove 65 into the annular space 9, and is returned by the end portion 11^b of the groove to the beginning of the sound record groove in space 6.

Altho the present invention has been de- 70 scribed in connection with the specific details of an embodiment thereof, it is not intended that these details shall be regarded as limitations upon the scope of the invention, except in so far as included in the accompanying claims.

I claim:

1. A sound record provided with a spiral sound record groove and an auxiliary groove, the latter groove beginning near the end 80 of the sound record groove, cutting across the record within the record groove and extending across the portion of the record occupied by the sound record groove, and terminating near the beginning of the sound 85 record groove.

2. A sound record provided with a spiral sound record groove and an auxiliary groove of slightly greater depth than the sound record groove, the latter groove beginning 90 near the end of the sound record groove, cutting across the record within the record groove and extending across the portion of the record occupied by the sound record groove, and terminating near the beginning of the sound 95 record groove.

3. A sound record disk provided with a spiral sound record groove and an auxiliary

groove of slightly greater depth than the sound record groove, the latter groove beginning near the end of the sound record groove, cutting across the record within the record groove and across the portion of the record containing the sound record groove and terminating near the beginning of the sound

record groove, the initial and terminal portions of the auxiliary groove merging into the sound record groove and the entire auxiliary groove having an angular magnitude on the record of less than 360° and more than 270° .
10

HENRY K. SANDELL.
